UNITED STATES PATENT OFFICE.

MAHLON G. BAILEY, OF SAN JOSE, CALIFORNIA.

RULE ATTACHMENT.

SPECIFICATION forming part of Letters Patent No. 718,300, dated January 13, 1903.

Application filed July 8, 1902. Serial No. 114,795. (No model.)

To all whom it may concern:

Be it known that I, MAHLON G. BAILEY, a citizen of the United States, residing at San Jose, in the county of Santa Clara and State of California, have invented a new and useful Rule Attachment, of which the following is a specification.

This invention relates to attachments to rules, more particularly to the ordinary carpenter's rule, and has for its object the production of an attachment thereto whereby bevels or angles may be accurately measured and determined.

Another object of the invention is to produce the attachment in shape to be applied readily to a rule already constructed, as well as to rules when manufactured; and the invention consists in certain novel features of the construction, as hereinafter shown and described, and specified in the claims.

In the drawings illustrative of the invention, Figure 1 represents a portion of an ordinary carpenter's rule with the improvement applied. Fig. 2 is a transverse section on the line II II of Fig. 1. Fig. 3 is a perspective view of the improved attachment detached.

As before stated, the device is more particularly applicable to the ordinary carpenter's rule, but may be applied to any form of similar implements or instruments. The two parts of the rule united by the "rule-joint" are represented at 10 11 with the usual graduations thereon, as shown.

The improvement which is the subject of the present application consists in a plate 12, circular in shape and attached to the rule-joint with its center coinciding exactly with the center of the joint-pivot. By this means the circular plate will retain the same position relatively with the parts 10 11 at all times and at all points of the movement of the latter. In rules of this character the members 10 11 are provided with binding-plates 13 14, extending some distance longitudinally thereof and forming a part of the rule-joint, the plate 13 extended in a circle, (indicated by dotted lines at 15 in Fig. 1,) while the plate 14 is formed with a curved recess in which the circle 15 fits, and in applying the plate 12 the latter is secured to the plate 13 and not to the plate 14, so that the member 11 is free to swing around beneath

the plate 12 when the rule is opened at the central joint. The plate 12 may be attached in any suitable manner, preferably by a clip 16, formed integral with the plate and adapted to engage the outer end of the member 10, and it may be rigidly secured thereto in any preferred manner, but is preferably made detachable therefrom, so that different disks 60 may be applied to the same rule interchangeably when it is desired to use the rule in different kinds of work. By this means of attachment the improved device may be readily applied to any ordinary carpenter's rule at any time required, which is a great convenience and adds materially to the value of the improvement, as it can be applied to the large number of rules already in use, and dependence need not, therefore, be necessarily placed 70 upon manufacturers of rules for its introduction or application. At the same time the attachment may be applied to the rule when manufactured.

The disk 12 is provided with graduations 75 representing the degrees of a circle, and any required number of the graduations may be employed, and for the purpose of illustration the graduations representing the angles most frequently employed are shown; but of course it will be understood that any number of graduations or graduations representing any desired angle may be employed, and the graduations may be varied for the use of different classes of mechanics or artisans. For 85 instance, for carpenters the graduations would be those most employed by them—such as the angles for roof-rafters, diagonal braces, cornice-miters, and the like—while for masons or machinists other sets of graduations might be provided, as the improvement is capable of a wide range of application without departing from the principle of the invention or sacrificing any of its advantages, and any one of these disks may be interchangeably used on the same rule.

The disk 12 may be formed of a very thin sheet of metal, so as not to interfere in any manner with the ordinary uses of the rule or render it cumbersome or add materially to 100 the expense and may be made of any desired size within the range of the width of the rule and the diameter of the portion 15 of the rule-joint.

The plate 12 should be made as large as possible to reduce the chances for error in measurements, but should not exceed in diameter the combined widths of the members 5 10-11, although, under certain circumstances, it might exceed in diameter the total width of the rule.

Having thus described my invention, what I claim is—

- 10 1. As a new article of manufacture, an attachment for rules consisting of a disk having a clip extended from one side and adapted to enclose one of the rule-sections with the center of the plate coinciding with the center 15 of the rule-joint pivot, and provided with radial graduations, substantially as described.

2. As a new article of manufacture, an attachment for rules consisting of a plate having a clip integral therewith and extended from one side and adapted to enclose one of the rule-sections, and means for detachably attaching said clip to the rule, the center of said plate coinciding with the center of the rule-joint pivot and provided with radial graduations, substantially as described. 20 25

In testimony that I claim the foregoing as my own I have hereto affixed my signature in the presence of two witnesses.

MAHLON G. BAILEY.
